UNITED STATES PATENT OFFICE.

JENS OLE ANTONIO AMUNDSEN, OF STAVANGER, NORWAY.

MACHINERY FOR DRYING MILK AND SIMILAR FOOD.

1,078,603.

Specification of Letters Patent. Patented Nov. 18, 1913.

Application filed April 30, 1912. Serial No. 394,249.

To all whom it may concern:

Be it known that I, JENS OLE ANTONIO AMUNDSEN, manager, subject of Norway, residing at Stavanger, Norway, have invented new and useful Improvements in Machinery for Drying Milk and Similar Food, of which the following is a specification.

My present invention relates to machinery for drying milk and similar food, and particularly to that kind of machinery, in which the drying is effected by means of a traveling endless band.

The invention is illustrated, partly diagrammatically, in the accompanying drawings, in which—

Figure 1 is a vertical longitudinal section through the drying chamber. Fig. 2 is a corresponding vertical cross section, 20 and Fig. 3 is an end view of the drying chamber.

As shown the drying chamber essentially comprises a chamber provided at one side or end with a comparatively large opening 25 —20— in which are so located two of the hollow cast iron cylinders —22, 23, 24, 25— carrying the endless metal-band —21—, that the opening is closed by the cylinders —22, 23— and which portion is supplied 30 with the milk, etc., and rid of the dried product, a vessel —26— being inserted through the chamber top and serving to vaporize or condense the milk, etc., before supplying the same to the band. The band 35 is driven by the cylinder —23— through its pins —27— projecting through holes in the edges of the band. The shaft —28— of this cylinder passes out through the chamber wall and on its outer portion is keyed a 40 driving pulley —29— for the belt —30—. The cylinder —24— has similar pins —27—, whereas the cylinders —22— and —25— may be smooth. Between cylinder —23— and some other one for instance —22— may 45 be arranged gearing, chain, etc., whereby cylinder —24— is caused to be driven from the other ones by means of the band —21—. Contrary to the other cylinders the cylinder —24— is adjustable so that it may be moved 50 horizontally toward —23— in order to hold the band at any time in a suitable tension on its drums and if necessary to enable repair or even removal of the cylinders through doors (not shown) arranged in the chamber walls.

The drying-chamber is built up of bricks,

wood with mass of insulation and sheet metal lining, or built in other suitable way as hereinafter described.

At the portion of the band —21— which covers the opening —20— the liquid to be dried is supplied and the dry-product is taken off. The supply takes place by means of a roller —31— engaging the cylinder —23— and projecting down into a cup —32— containing the milk, etc. The removal of the dried product is effected by a knife —9— which is pressed against the band near the cylinder —22—.

In the following for simplicity sake still is spoken only of milk as the food to be dried.

Through the top of the drying-chamber a double-wall metal-vessel —26— is inserted, as mentioned. Between its outer cap —33— and its inner wall —34— a water space is left in which is circulated water by means of inlet and outlet tubes —35, 36—. By the heat in the chamber the water is heated to boiling and is consequently maintained at 100 centigrades. The vapor produced is conducted to a condenser-pot. The inner vessel —34— serves to take up milk to be vaporized or condensed. The milk is introduced continuously and the vessel is provided with a tightly closing metal-hood (not shown), from which passes out a wide tube with a fan for withdrawal of water-vapors from the milk. The latter is heated and highly condensed in the vessel, it being constantly during the process agitated by means of a stirrer —37— on the shaft —38—. When the desired degree of condensation is obtained, which is controlled by an aerometer, the milk is conducted out through a tube at the bottom, and new milk is introduced from above in the same quantity. The heat consumed for effecting this condensation is obtained from the drying chamber practically without additional expense. After having in this manner rid the milk of from $\frac{1}{2}$ to $\frac{1}{4}$ of its original percentage of water it is in the drying-chamber further rid of so much water, that only 2-5% of water is left. The milk is continuously introduced into the cup —32—, is taken along by the feeding roller —31— and is deposited as a thin uninterrupted film or layer on the slowly traveling metal band —21—. By means of the latter the milk film is passed into the drying-chamber and is within the same subjected to superheated clean air circulating through

the chamber in a manner as more fully described hereinafter. When reaching the knife —9— the product has the reduced degree of moisture above mentioned, *i. e.* it has 5 been converted into a practically dry mass which is scraped off on the whole width of the band by means of the knife —9— and falls from the same down into a box or a vessel.

10 In order to control the circulation of air in the drying-chamber the following arrangement is provided: The top, bottom and the front wall at —20— are made solid, but the back-wall and also the both side-walls 15 (located in planes parallel to that of the drawing) are made double. The inner wall or lining —39— consists of perforated bricks and between the same and the outer wall —40—, which is built up of usual solid 20 bricks, is left an air circulating channel —41— having a width of say 15 centimeters. Within the chamber radiator-elements —42, 25 —43— are arranged at suitable places. At the top of the back-wall of the chamber or furnace a suction fan —44— is arranged, which through a pipe —45— is connected with the channel —41— and through a branch pipe —46— directly with the inner space of the chamber. From another fan —47— super- 30 heated air is pressed through pipes —48, 49— into the chamber at its front viz: above the band —21— and below the same, thus at the top parallel to its traveling direction and at the bottom oppositely the same. 35 Consequently the hot air is forced toward the back-wall of the chamber, and all the moisture developed from the milk film on the band is instantly drawn away by means of the fan —44—. By controlling the tem- 40 perature of the superheated air pressed in through —48— and —49— the degree of desiccation may be exactly regulated which also to some extent may be effected by varying the velocity of the band —21—. The 45 heat effecting the drying may also be produced by a fire arranged under the chamber or by means of a system of water tubes, or by a system like that used in usual bakers' ovens, when the chamber is built up of 50 bricks or the like.

The length of the band —21— and the diameter and length of the cylinders may be varied according to requirements or to the desired capacity of the apparatus. Moreover, 55 the invention is not limited to the arrangement of parts shown in the drawing. Thus for instance the cylinder —22— may be placed more to the left, about at the cross —50—, the feeding roller —31— with its 60 cup —32— beneath the cylinder —23—, and the traveling direction of the band reversed.

In some cases it also may be suitable to produce casein and raw milk-sugar (dried whey) on the same apparatus. When dry- 65 ing the whey the process is just as for

milk, and during such process the cheese mass is pressed. When the whey is dried, all further heating for the day ceases. The furnace is hot enough for drying the casein. The milk stirrer is replaced by another 70 stirrer (having about the same construction as that used in the coffee-roaster termed "Sirocco"). The cheese mass is poured into the vessel —34—, in which it is constantly agitated until it is dried, whereupon the 75 mass through an opening in the vessel is thrown out into a pipe or a channel and through the same directly into the mill. When the casein has been ground it is quite ready for export to the galalith-factories. 80 The dried whey is used partly for export to the milk-sugar refineries and partly as a fodder.

Having now described my invention, what I claim as new and desire to secure by Letters Patent is:—

1. In an apparatus for drying fluid substances, etc., the combination of a drying chamber having a large opening in the front end thereof, an endless metal band passing 90 into said chamber and partially closing said opening, means for feeding fluid to the in-going portion of the band, means for scraping off the dried product from the out-coming portion of the band, pipes for blowing in superheated air at the front part of the chamber in parallel current direction to the in-going portion of the band, pipes for blowing in superheated air at the front part of the chamber in counter-current direction 100 to the outcoming portion of the band, and outlet pipes for withdrawing the moist air from the rear end of the chamber.

2. In an apparatus for drying fluid substances, etc., the combination of a drying 105 chamber having a large opening in the front end thereof, and double wall in the rear end thereof, the inner one of said walls being perforated, an endless metal band passing into said chamber and partially closing said 110 opening, means for feeding fluid to the in-going portion of the band, means for scraping off the dried product from the out-coming portion of the band, pipes for blowing in superheated air at the front part of the 115 chamber in parallel current direction to the in-going portion of the band, pipes for blowing in superheated air at the front part of the chamber in counter-current direction to the out-coming portion of the band, and outlet pipes for withdrawing the moist air from the rear end of the chamber, one outlet pipe being inserted into the space between the double rear wall parts of the chamber, and another outlet pipe being inserted through 125 the top wall of the chamber near its rear end.

3. In an apparatus for drying fluid substances, etc., the combination of a drying chamber having a large opening in the front 130

end thereof, an endless metal band passing into said chamber and partially closing said opening, rollers for supporting the band, two of which are located in the said large opening, so as to provide between them a freely locating straight portion of the band, means for feeding milk to the said straight band portion near its in-going portion; means for scraping off the dried product from the straight band portion near its out-going portion, pipes for blowing in superheated air at the front part of the chamber in parallel-current direction to the in-going portion of the band, pipes for blowing in superheated air at the front part of the chamber in counter-current direction to the out-going portion of the band, and outlet pipes for withdrawing the moist air from the rear end of the chamber.

4. In an apparatus for drying fluid substances, etc., the combination of a drying chamber having a large opening in the front end thereof, and a double wall in the rear end thereof, the inner one of said walls being perforated, an endless metal band passing into said chamber and partially closing said opening, rollers for supporting the band, two of which are located in the said

large opening, so as to provide between them a freely locating straight portion of the band, means for feeding milk to the said straight band portion near its in-going portion, means for scraping off the dried product from the straight band portion near its out-going portion, pipes for blowing in superheated air at the front part of the chamber in parallel-current direction to the in-going portion of the band, pipes for blowing in superheated air at the front part of the chamber in counter-current direction to the out-going portion of the band, and outlet pipes for withdrawing the moist air from the rear end of the chamber, one outlet pipe being inserted into the space between the double rear wall parts of the chamber, and another outlet pipe being inserted through the top wall of the chamber near its rear end.

In testimony whereof I have signed my name to this specification in the presence of two subscribing witnesses.
